(57) **CLAIM**

The ornamental design for a pedal crank, as shown and described.

DESCRIPTION

FIG. 1 is a front perspective view of a pedal crank showing our new design;

FIG. 2 is a left side elevation view thereof, to which the right side elevation view is a mirror image;

FIG. 3 is a top plan view thereof;

FIG. 4 is a bottom plan view thereof; and,

FIG. 5 is a front elevation view thereof.

The broken lines in the drawings illustrate portions of the pedal crank that form no part of the claimed design.
